Cosmetic Company, Inc., New York, N. Y., a
corporation of New York

Application July 12, 1939, Serial No. 85,962

Term of patent 14 years

To all whom it may concern:

Be it known that I, Louise Fabisch, a citizen
of the German Reich, residing at New York, in
the county of New York, city and State of New
York, have invented a new, original, and orna-
mental Design for a Combination Lipstick Casing
and Mirror, of which the following is a specifica-
tion, reference being made to the accompanying
drawing, forming a part thereof.

Fig. 1 is a top plan view of the combination
lipstick casing and mirror showing my design
with lid in closed position.

Fig. 2 is a side elevational view thereof,
Fig. 3 is a perspective view of the article with

lid in open position.

The characteristic features of the design reside
in the casing of the configuration shown having
a lid hinged along one of the longitudinal sides
of said casing and having a projecting panel
at one end thereof provided with a pull chain
secured thereto carrying a finger hold at its free
end.

I claim:

The ornamental design for a combination lip-
stick casing and mirror, substantially as shown
and described.

LOUISE FABISCH.
